UNITED STATES PATENT OFFICE.

MEYER KEILSON, OF NEW YORK, N. Y.

ALARM DEVICE.

1,130,408.

Specification of Letters Patent.

Patented Mar. 2, 1915.

Application filed September 10, 1912. Serial No. 719,601.

To all whom it may concern:

Be it known that I, MEYER KEILSON, a citizen of the United States, and a resident of New York, county and State of New York, have invented a certain new and useful Improvement in Alarm Devices, of which the following is a full, clear, and exact specification.

This invention relates to a class of devices 10 adapted to be used especially in conjunction with drip pans.

My invention has for its object primarily to provide a form of device designed to be applied upon a pan, or similar receptacle 15 when used to receive the drip water from a refrigerator, ice chest, or the like, and which is adapted to automatically sound an alarm when the receptacle is sufficiently filled with water so as to be emptied in due time to 20 prevent the receptacle from overflowing.

Another object of the invention is to provide a spring actuated clamp which serves to permit the device to be readily attached, or detached from the receptacle whereby the 25 device may be used in succession upon several receptacles, and a further object of the invention is to provide an alarm device of a compact, durable, and efficient form.

A practical embodiment of the invention 30 is represented in the accompanying drawing forming a part of this specification in which similar characters of reference indicate corresponding parts in all the views, the said invention being more fully described herein- 35 after, and then pointed out in the appended claims.

In the drawing, Figure 1 is a fragmentary 40 view of a drip pan with one form of my improved alarm device applied thereto. Fig. 2 is an end view of the device, part of which is broken away. Fig. 3 is a section taken on the line II-II of Fig. 1, and Fig. 4 is a section taken on the line III-III of Fig. 1.

The alarm device 10 is adapted to be detachably applied upon any suitable form 45 of pan, or receptacle, as 11, which may be used to receive the drip water from a refrigerator, ice chest, or the like, and said device 50 has a supporting member, or straddle bar 12 composed of two arms 13 and 14 which are spaced apart in parallel relation so as to provide a slot 15 therebetween for reception 55 of the wall of the receptacle over which said arms are disposed when the device is applied thereon, as will be hereinafter more fully

described. Each of the arms 13 and 14 are substantially U-shaped, as shown in Fig. 3, whereby recesses 16 and 17 are provided. Upon the top of both of the arms 13 and 14 60 is an integrally formed transverse bar 18 which is of a length to extend some distance beyond the arms 13 and 14, and said transverse bar is also preferably U-shaped whereby a recess 19 is formed.

Serving as a means to permit the supporting member, or straddle bar 12 to be yieldingly held upon the wall of the receptacle, in order to permit the device to be readily attached or detached therefrom, in the recess 17 of the arm 14 is a spring attached 70 actuated clamp 20. The clamp 20 consists of a strip, or elongated plate 21 having its ends curved inwardly of the recess 17, and at spaced intervals upon one surface of said plate are two projecting pins 22 and 23. Both of the pins 22 and 23 are movably 75 guided through openings in the transverse wall of the U-shaped arm 14 of the straddle bar, and encircling each of the pins between said transverse wall and the elongated plate 21 is a spiral spring 24 and 25. The springs 24 and 25 normally serve to force the elongated plate 21 of the clamp toward the arm 13 of the straddle bar so as to yieldingly 80 engage the opposed surface of the wall of the receptacle when the straddle bar is disposed thereover, as shown in Fig. 1.

To the transverse wall of the U-shaped arm 13 of the straddle bar is secured an 85 alarm 26 which is preferably of the form of a bell of the well known type which is adapted to be wound by rotating a part of its casing, and which is sounded by moving a stem, 90 as 27, which projects outwardly of the stationary part of the casing of the alarm. The stem 27 is of sufficient length to extend 95 through an opening in the transverse wall of the top U-shaped bar 18 of the straddle bar, and said stem is adapted to be moved 100 in a direction inwardly of the casing of the alarm for sounding it by a spring controlled plate 28. The plate 28 is preferably seated in the recess 19 of the U-shaped bar 18, and has one of its ends pivoted, at 105 29, at the free end of said U-shaped bar. The plate 28 is of a length to extend some distance beyond the other end of the bar 18. Upon the top of the bar 18, and at its end 110 to which is pivoted the plate 28, is held one end of a spring 30 which is curved so that its free end is in contact with the free end of

the plate 28, in order to normally serve to force said plate in contact with the stem 27 of the alarm.

Projecting from the end of the transverse 5 U-shaped bar 18 opposite to the end to which is pivoted the plate 28, is a lever 31. The lever 31 is of a length to extend toward the center, or beyond the center of the receptacle, and at one end of said lever is held a 10 float, as 32. The lever 31 is also pivoted, or fulcrumed intermediate its length, as at 33, to the U-shaped bar 18, whereby an extension 34 is provided and said extension is adapted to engage the spring controlled 15 plate 28 for directing this plate upwardly so as to be free from engagement with the stem 27 of the alarm when the float 32 is lowered in the receptacle, as indicated by dotted lines at 35, when there is no liquid 20 therein, or when it is only partially filled. When the receptacle is sufficiently filled with liquid whereby it should be emptied to avoid overflowing the float will be carried upon the surface of the liquid, and the lever 25 31 will be moved to a position in alignment with the plate 28. The extension 34 will thereby be freed from engagement with the plate 28, and the tension of the spring 30 will force said plate in a direction to engage 30 and move the stem 27 for sounding the alarm of the device.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to 40 make such changes as fairly fall within the scope thereof.

Having thus described my invention, I claim as new and desire to secure by Letters Patent:

45 1. An alarm, comprising in combination,

Copies of this patent may be obtained for five cents each, by addressing the "Commissioner of Patents, Washington, D. C."

a supporting member adapted to be attached to a liquid containing vessel, a movable stem, a spring controlled movable plate mounted upon the said supporting member and adapted to normally hold said movable stem in operative position to sound said alarm, a lever pivoted at a point near one of its ends to the said supporting member, whereby the end of said lever will engage the said spring controlled movable plate to 50 free said plate from contact with said movable stem when the opposite end of said lever is lowered, a float carried on said lever at its said opposite end and adapted to swing the said end upwardly, thereby allowing the spring controlled plate to descend into engagement with the movable stem of the alarm when the liquid in the vessel rises to a predetermined height.

2. An alarm, comprising in combination, 65 a supporting member adapted to be attached to a receptacle, a movable stem adapted to sound said alarm, a spring controlled movable plate mounted upon the said supporting member and adapted to normally hold said movable stem in operative position to sound said alarm, a lever pivoted at a point near one of its ends to the said supporting member, whereby the end of said lever will engage the said spring controlled 70 movable plate to free said plate from contact with said movable stem when the opposite end of said stem is lowered, means carried on the said opposite end of said lever and adapted to swing the said opposite end upwardly thereby allowing the spring controlled movable plate to descend into engagement with the movable stem of the 75 alarm.

This specification signed and witnessed 85 this seventh day of September A. D. 1912.

MEYER KEILSON.
